Filed Nov. 19, 1959, Ser. No. 854,151

5 Claims. (Cl. 269—583)

This invention relates to the production of unsymmetrical-dialkylhydrazines in which the alkyl groups each contain from 1 to 3 carbon atoms and specifically to the production of unsymmetrical-dimethylhydrazine, herein referred to for the sake of brevity as DMH. More particularly, this invention relates to the catalytic hydrogenation of nitrosodimethylamine to produce DMH. While the invention will be hereinafter described, for the most part, in connection with the production of the preferred embodiment, DMH, it will be understood it is not limited thereto and includes the preparation of unsymmetrical-dialkylhydrazines such as diethyl-, dipropyl, unsymmetrical-methyl-ethyl-, and unsymmetrical-ethylpropylhydrazines.

DMH is used as a special fuel in the guided missile and rocket fields. Reduction of nitrosodimethylamine to DMH by treatment with metallic zinc and acetic acid or aluminum and caustic soda, expensive reducing agents, has been suggested. In recent years, much effort has been devoted to the development of hydrogenation procedures for reducing nitrosodimethylamine to DMH. All procedures heretofore suggested, to the best of our knowledge and belief, have involved liquid phase procedures under high pressures employing catalysts such as platinum, palladium or Raney nickel. For example, British Patent 801,534 of 1958 refers to the use of hydrogen pressures between 1,200 and 2,000 p.s.i.g. and states that optimum results are obtained at about 1,600 p.s.i.g. Such procedures for reducing nitrosodialkylamines are objectionable for a number of reasons, among which may be mentioned, they require expensive autoclaves or other costly pressure equipment and DMH yields and productivity rates are relatively low.

It is a principal object of the present invention to provide a catalytic process of hydrogenating nitrosodialkylamines having from 1 to 3 carbon atoms in the alkyl groups, particularly nitrosodimethylamine, which can be carried out at relatively low pressures and hence requires for its practice inexpensive low pressure equipment.

Another object of this invention is to provide such catalytic process in which the reaction is carried out in the vapor phase with high yields and relatively high productivity rates.

Still another object of the present invention is to provide such catalytic process in which the catalyst has a relatively long life, appreciably longer than the life of the catalysts in heretofore known liquid phase processes involving the passage of hydrogen and the nitrosodialkylamine in the liquid phase through a fixed bed of catalyst particles.

Other objects and advantages of this invention will be apparent from the following detailed description thereof.

In accordance with the present invention, nitrosodialkylamines in which the alkyl groups contain from 1 to 3 carbon atoms, particularly nitrosodimethylamine, are hydrogenated to produce unsymmetrical dialkylhydrazines, particularly DMH, by passing the nitrosodialkylamines in the vapor phase and hydrogen, employing at least 20 mols of hydrogen per mol of nitrosodialkylamine, desirably from 20 to 600 mols of hydrogen per mol of nitrosodialkylamine, through a bed of platinum catalyst particles under a hydrogen pressure above atmospheric, desirably not exceeding about 500 p.s.i.g. and preferably from 75

2

to 200 p.s.i.g. and at a temperature of from 80° to 165° C., preferably 85° to 100° C.

It is important that a large excess of hydrogen be used. The use of a large excess of hydrogen, namely at least 20 mols of hydrogen per mol of nitrosodialkylamine under the conditions of pressure and temperature above given and employing a platinum catalyst results in high yields and productivity rates and permits the conduct of the reaction in the vapor phase.

The process is carried out by introducing the nitrosodimethylamine along with hydrogen into a vaporizer and passing the resultant vapor mixture through the catalyst bed at a vapor space velocity of from 40 to 2,000 reciprocal hours, preferably from 50 to 500 reciprocal hours, based on the nitrosodimethylamine at STP (0° C. and 760 mm. of mercury). Desirably an aqueous solution of nitrosodimethylamine is fed to the vaporizer for economic reasons and to aid in the volatilization of the nitrosodimethylamine at relatively low temperatures. Instead of an aqueous solution, the nitrosodimethylamine may be dissolved in other suitable solvents, such, for example, as acetic acid, ethyl alcohol, methyl alcohol, mixtures of any of these solvents with water and mixtures thereof without water.

Preferably the catalyst is a supported catalyst; activated alumina desirably is used as the support. Such catalyst can be produced, for example, by coating the support with the platinum metal to provide a supported catalyst containing from 0.1% to 5%, preferably 0.1% to 2%, by weight of the metal on the carrier particles. For example, a platinum salt, such as platinic chloride, may be deposited on activated alumina particles having a size of from 4 to 50 mesh (U.S. screen size), the thus coated particles then treated with sodium hydroxide and the platinum oxide thus formed reduced to platinum. Alternatively, platinum may be directly deposited on the carrier particles.

In the accompanying drawing, the single figure shows diagrammatically, for purposes of exemplification and to facilitate a better understanding of this invention, a preferred arrangement of equipment for carrying out the process of this invention.

In this drawing, 10 indicates a vaporizer which may be of any well-known type and which in operation is heated to a temperature of from 80° to 165° C., preferably 85° to 100° C., and is maintained at a pressure above atmospheric, preferably 75 to 200 p.s.i.g. A solution of nitrosodimethylamine, preferably aqueous, containing from 10% to 75% nitrosodimethylamine and 25% to 90% solvent is pumped into the vaporizer 10 by a pump 11 through line 12. Hydrogen is supplied to vaporizer 10 through line 13 by pump 14. The nitrosodimethylamine and water vaporize in vaporizer 10 and mix with the hydrogen, the reactants being supplied in a ratio of 20 to 600 mols of hydrogen per mol of nitrosodimethylamine.

From the vaporizer 10, the vapor mixture passes up through a catalyst bed 15 contained in the catalyst reactor 16 communicably connected with vaporizer 10 by line 17. The catalyst bed is thus maintained under a hydrogen pressure above atmospheric. Catalyst bed 15 is composed of platinum catalyst particles. The reaction mixture in the vapor phase leaves the catalyst reactor 16 through line 18 and enters the partial condenser 19. Condenser 19 effects partial condensation of the dimethylhydrazine along with water and by-products formed, chiefly dimethylamine and ammonia. Residual reaction gases are scrubbed with water by passage through scrubber 21 where remaining dimethylamine, ammonia, dimethylhydrazine and water are removed from the hydrogen gas stream. The hydrogen exits from scrubber 21 through line 22 and may be recycled to the pump 14 and fed to

the vaporizer under desired pressure. The crude DMH is collected in the receiver 23.

Vaporizer 10 and the catalyst reactor 16 may be of stainless steel or other materials resistant to corrosion by the reactants and the reaction products. Since the operating pressures do not exceed 500 p.s.i.g. and preferably are within the range of from 75 to 200 p.s.i.g., relatively inexpensive low pressure equipment may be used.

The following examples are illustrative of the process of this invention. It will be appreciated that this invention is not limited to these examples. In the examples, parts and percentages are on a weight basis, temperatures in ° C. The examples were carried out in equipment of the general type shown in the drawing.

Example I

An aqueous solution containing 53% nitrosodimethylamine was fed to the top of the vaporizer where it was vaporized and mixed with hydrogen in a mol ratio of 85 mols of hydrogen per mol of nitrosodimethylamine. The vaporizer was maintained at 87°, the reactants passed down through the vaporizer and the resultant vapor mixture was passed up through a catalyst bed in the catalyst reactor at a vapor space velocity of 60 reciprocal hours based on the nitrosodimethylamine at STP. The catalyst bed was composed of 0.43% platinum on 8 to 14 mesh activated alumina. It was maintained under a pressure of 100 p.s.i.g. The reactants entered the bed at 88°; the maximum temperature within the bed was 95°.

The reactor effluent from the catalyst reactor was partially condensed by cooling to 0° and then passed through water scrubbers. Analysis of the resulting aqueous solution showed that the reaction product contained:

Component:	Percent
DMH	34.4
Dimethylamine	4.3
Ammonia	1.6
Nitrosodimethylamine	3.6
Water	56.1

A yield of 80% of DMH was thus obtained based on the nitrosodimethylamine fed to the catalyst reactor.

Example II

In this example, an aqueous solution containing 25.3% nitrosodimethylamine was fed to the top of the vaporizer, where it was vaporized and mixed with hydrogen in a mol ratio of 255 mols of hydrogen per mol of nitrosodimethylamine. The vaporizer was maintained at 86°. The reactants passed down therethrough and the resultant vapor mixture was passed up through a catalyst bed composed of 0.1% platinum on 8-14 mesh activated alumina. The reactants passed through the catalyst bed at a vapor space velocity of 75 reciprocal hours based on the nitrosodimethylamine at STP. The reactor was operated at a pressure of 100 p.s.i.g. The reactants left the vaporizer at 86° and passed up through the catalyst bed; the maximum temperature within the catalyst bed was 92°.

The reactor effluent was partially condensed, and the residual gaseous mixture passed through water scrubbers. The condensate was combined with the product recovered in the water scrubbers. Analysis of the resulting aqueous solution showed that the reaction product contained:

Component:	Percent
DMH	18.0
Dimethylamine	1.8
Ammonia	0.7
Nitrosodimethylamine	.2
Water	79.3

A yield of 87.5% of DMH was obtained based on the nitrosodimethylamine fed to the catalyst reactor.

It is preferred to employ highly concentrated or essentially pure hydrogen but diluents may be present so long

as the disclosed conditions of proportions, temperatures and pressures are maintained.

It will be noted that the present invention provides a process for synthesizing dialkylhydrazines, particularly DMH, involving the passage of the dialkylnitrosoamine in the vapor phase admixed with hydrogen through a bed of platinum catalyst particles at pressures from just above atmospheric to 500 p.s.i.g., preferably from 75 to 200 p.s.i.g., and temperatures of from 80° to 165° C., preferably 85° to 100° C. Accordingly the process can be carried out in inexpensive low pressure equipment. The present process is advantageous not only in that it results in high yields and productivity rates involving as it does a vapor phase hydrogenation of the nitrosodialkylamines, but also in that the temperature conditions within the catalyst reactor can be controlled more readily in the present vapor phase process as compared with liquid phase procedures. The catalyst remains active for long periods of time of the order of 100 hours to 1,000 hours and longer. This attribute of the process is particularly notable with the use of the large excess of hydrogen, i.e. at least 20 mols of hydrogen per mol of nitrosodialkylamine at a reaction temperature of from 80° to 165° C.

It is to be understood that this invention is not to be restricted to the present disclosure otherwise than as defined in the appended claims.

What is claimed is:

1. The process of hydrogenating nitrosodialkylamines to produce unsymmetrical-dialkylhydrazines, in which the alkyl groups contain from 1 to 3 carbon atoms, which process comprises passing the nitrosodialkylamine in the vapor phase and hydrogen in the proportions of at least 20 mols of hydrogen per mol of nitrosodialkylamine through a bed of platinum catalyst while maintaining the catalyst bed under superatmospheric hydrogen pressure and at a temperature within the range of from 80° to 165° C. and removing from the catalyst bed, in the vapor phase, the reaction mixture containing the unsymmetrical-dialkylhydrazine.

2. The process of hydrogenating nitrosodialkylamines to produce unsymmetrical-dialkylhydrazines, in which the alkyl groups contain from 1 to 3 carbon atoms, which process comprises passing the nitrosodialkylamine in the vapor phase and hydrogen in the proportions of from 20 to 600 mols of hydrogen per mol of nitrosodialkylamine through a bed of platinum catalyst while maintaining the catalyst bed under superatmospheric hydrogen pressure within the range of from 75 to 200 p.s.i.g. and at a temperature within the range of from 80° to 165° C. and removing from the catalyst bed, in the vapor phase, the reaction mixture containing the unsymmetrical-dialkylhydrazine.

3. The process of hydrogenating nitrosodimethylamine to produce unsymmetrical-dimethylhydrazine, which process comprises passing nitrosodimethylamine in the vapor phase and hydrogen in the proportions of at least 20 mols of hydrogen per mol of nitrosodimethylamine through a bed of platinum catalyst while maintaining the catalyst under superatmospheric hydrogen pressure of up to about 500 p.s.i.g. and at a temperature within the range of from 80° to 165° C. and removing from the catalyst bed, in the vapor phase, the reaction mixture containing the unsymmetrical-dimethylhydrazine.

4. The process of hydrogenating nitrosodimethylamine to produce unsymmetrical-dimethylhydrazine, which process comprises passing nitrosodimethylamine in the vapor phase and hydrogen in the proportions of from 20 to 600 mols of hydrogen per mol of nitrosodimethylamine through a bed of supported platinum catalyst while maintaining the catalyst bed under a hydrogen pressure of from 75 to 200 p.s.i.g. and at a temperature within the range of from 80° to 165° C. and removing from the catalyst bed, in the vapor phase, the reaction mixture containing the unsymmetrical-dimethylhydrazine.

5. The process of hydrogenating nitrosodimethylamine to produce unsymmetrical dimethylhydrazine, which process comprises continuously introducing an aqueous solution of dimethylnitrosoamine containing from 10 to 75 weight percent dimethylnitrosoamine and 25% to 90% water and hydrogen in the proportions of from 20 to 600 mols of hydrogen per mol of nitrosodimethylamine into a vaporizer maintained at a temperature of from 80° to 165° C. and under a pressure of from 75 to 200 p.s.i.g., passing the resultant vapor mixture from said vaporizer through a fixed bed of catalyst consisting of supported platinum on an activated alumina carrier having a particle size of from 4 to 50 mesh, the amount of platinum on the

carrier particles being from 0.1% to 5% by weight while maintaining the catalyst bed under a hydrogen pressure of from 75 to 200 p.s.i.g. and at a temperature of from 80° to 165° C., continuously removing the reaction products in the vapor phase from the catalyst bed, and recovering the unsymmetrical dimethylhydrazine from the reaction products.
